William Campbell, Gibson, New Hampshire,

Letters Patent.

The Schedule, referred to in these Letters Patent, and making part of the same, containing a description in the words of the said William Campbell himself of his "Improvement in the socket Shank and haft."

Be it known that I William Campbell, of Gibson, in the County of Cheshire in the State of New Hampshire, have invented a new and useful machine or tool called "The socket Shank and haft" and that the following is a full and exact description thereof. The use of the socket shank and haft is to hold the nail for making holes for the insertion of pins in leather, whether in the manufacture of shoes and boots, or any other manner, or manner of leather which may be made. It is constructed as follows.

1st. There is a socket shank inserted in wood or any other material used for a handle far enough to be set firmly, and protecting from the wear of other material three eighths of an inch with a screw thread on the part that projects - the diameter of the protruding part, five sixteenths of an inch - in this part is a square socket to receive the shank of the nail, this socket may be made triangular, or slided or surrounded by a square but the square is preferable. This socket shank may be of iron or steel - 3 1/2". This is a sort of bridle or form setting the shank of the nail in the socket 2" with a diameter of an inch in length the rim of the nail thinnest at the forward part to give a prospect like to the haft. 3 1/2" - a screw to fit the nail inserted into the forward part of it, with a round hole in it and with a screw part on it forward of the termination of the nail on which a wrench is applied for receiving tightening or removing this screw. The hole in it must be large enough to receive the largest sized nail to be used and must be smaller than the forward part of the shank of the nail to be used. - The design of this part is to receive and fasten the nail when inserted.

inserted into the socket shank. The awl used must have a four equal sided shank, tapering back, fitting the square hole in the socket shank first described and bounded off flattened on the front or record. To set the awl the forward screw above described must be removed with the screw key. The awl is then fixed in the socket shank and the screw being replaced with the worm the awl will be firmly set and fastened. A set of any size which can be passed through the hole in the forward screw may be used in the same shaft. A dangerous size may be readily substituted for a different size. The size of the shank of the different awls to be the same. The shaft may also be used for assuming all constituents suitably to fit it. Claims as to improvement the square form of the socket hole first described for receiving the shank of the awl and the conical nut, also the mode of securing the awl by the forward screw as above described, also the manner above described of combining the several parts for forming the entire "Aawl".
